(57) **CLAIM**

The ornamental design for a mounting bracket for a lamp as shown and described.

DESCRIPTION

FIG. 1 is a front, left and top perspective view of a mounting bracket for a lamp, showing my new design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is an enlarged top plan view thereof.

FIG. 8 is an enlarged bottom plan view thereof.

FIG. 9 is another front, left and top perspective view of the mounting bracket for a lamp in a first usable state.

FIG. 10 is another front, left and top perspective view of the mounting bracket for a lamp in a second usable state; and,

FIG. 11 is an enlarged view of detail 11 in FIG. 1.

The dashed broken lines depict portions of the mounting bracket for a lamp that form no part of the claimed design. The dot-dash broken lines in FIGS. 1 and 11 depict the boundaries of the enlargements and form no part of the claimed design.
